UNITED STATES PATENT OFFICE.

LOUIS B. HASBROUCK, OF ELMIRA, NEW YORK, ASSIGNOR TO ECLIPSE TEXTILE DEVICES, INC., OF ELMIRA, NEW YORK, A CORPORATION OF NEW YORK.

HOLDER FOR YARN CONES.

Original application filed April 8, 1926, Serial No. 100,486. Divided and this application filed March 14, 1927. Serial No. 175,081.

This invention relates to an improved holder for a cone of yarn, and aims to provide a simple device for holding a cone of yarn firmly in desired position, and one to 5 which the cone of yarn may be readily and quickly applied, and from which it may be as easily removed.

The holder may be used to support a cone of yarn in a dyeing machine, such as that 10 shown in my copending application, Serial No. 100,486, filed April 8, 1926, of which the present application is a division, or for holding a cone of yarn for any other desired purpose.

15 The invention will be described with reference to the annexed drawing showing a holder embodying the invention, and on the holder, a cone of yarn sectioned on the axis of the holder.

20 The cone holder illustrated has a rod 10 of materially less diameter than the core C¹ of a cone of yarn C to be supported on the holder. The rod 10 carries at its outer end, an adjustable plunger 11 having a frusto-conical head 12 for engaging the core of the cone at or near its smaller end. At the inner end of the rod 10 is a gripping member 13 for engaging the core of the cone at or near its larger end. The member 13 has a threaded outer surface which forms a corresponding 25 thread in the inner surface of the cardboard core C¹ when the core is screwed upon it.

30 The rod 10 is supported from its inner end in any desired manner, for example, the inner end of the rod may be provided with an integral extension or shaft 14 which may be held either fixedly or rotatably in any convenient support, bearing, or socket.

35 In the use of the holder, the plunger 12 is adjusted in accordance with the length of the cones to be mounted. A cone may then be mounted on the holder very quickly and easily, as it is necessary only to slip its core over the rod 10 and then screw the 40 larger end of the core upon the threaded member 13 until the inner end of the core is brought into firm contact with the head 12. The core and the yarn are then firmly 45 held in fixed relation to the rod 10. To re-

move the core, it is necessary only to unscrew the core from the threaded member 13.

What I claim is:

1. A holder for a cone of yarn, comprising a rod of less diameter than the core of the cone, and a frusto-conical member having a sharp projecting screw thread and fixed on said rod at such distance from the end of the rod that the larger end of the core of the cone may be screwed upon said member so as to draw the inner end of the core into contact with the end of the rod. 55

2. A holder for a cone of yarn, comprising a mandrel having a frusto-conical screw-threaded larger end adapted to engage the interior of the cone to draw the inner end of the mandrel into contact with the smaller end of the cone on relative rotation of the 60 mandrel and the cone. 65

3. A holder for a cone of yarn, comprising a frusto-conical mandrel having at its larger end a sharp projecting screw thread to engage the interior of the cone to draw it upon the mandrel on relative rotation of 70 the mandrel and the cone. 75

4. A holder for a cone of yarn, comprising a mandrel having two spaced engaging surfaces of different diameters, the larger of said surfaces being frusto-conical and 80 screw-threaded to engage the interior of the cone of yarn to draw the cone into contact with the other engaging surface on relative rotation of the cone and the mandrel. 85

5. A holder for a cone of yarn, comprising a rod, two spaced engaging members of different diameters fixed on said rod, the larger of said members being frusto-conical and screw-threaded to engage the interior of the cone of yarn to draw the cone into 90 contact with the other engaging member on relative rotation of the cone and the mandrel, and means for varying the distance between the said engaging members to provide for holding cones of different dimensions. 95

In testimony whereof I have hereunto set my hand.

LOUIS B. HASBROUCK.
